(57) **CLAIM**

The ornamental design for a connector for printed circuit boards, as shown and described.

DESCRIPTION

FIG. 1 is a top plan view;

FIG. 2 is a front elevation;

FIG. 3 is a bottom plan view;

FIG. 4 is a right-side elevation;

FIG. 5 is a rear elevation;

FIG. 6 is a frontal perspective view;

FIG. 7 is a rear perspective view; and,

FIG. 8 is a cross sectional taken along line 8—8 in FIG. 2.

The present design is characterized by a tongue intervening between two recesses that are disposed in a top of the connector and intermediate between its lateral sides, and also by a tapered ridge continuing to the rear ends of the tongue and recesses.
